UNITED STATES PATENT OFFICE

105,616

DESIGN FOR A FISHING REEL

John V. Schafer, Bronson, Mich., assignor to
Bronson Reel Company, Bronson, Mich., a cor-
poration of Michigan

Application July 29, 1935, Serial No. 57,853

Term of patent 14 years

To all whom it may concern:

Be it known that I, John V. Schafer, a citizen of the United States, residing at Bronson, Branch County, Michigan, have invented a new, original, and ornamental Design for a Fishing Reel, of which the following is a specification.

The design is shown in the accompanying drawing, which forms a part thereof, and in which:

Figure 1 is a perspective view of a fishing reel, showing my new design; and

Figure 2 is a very much enlarged section on line 2—2 of Figure 1.

The essential, or dominant, feature of the design is the progressive increase in the diameter of the head portion. More specifically, the head portion of the reel shown presents a wide central

portion, with a narrower portion at each end, the outer narrow portion being of smaller diameter than the central portion, and the inner narrow portion being of larger diameter than the central portion. The radial offsets where the narrow portions join the central portion are of the same order of magnitude as each other, and of the same order of magnitude as the axial dimensions of the narrow portions, and, in the embodiment of Figure 1, substantially one-tenth of the axial dimension of the central cylindrical portion 16.

I claim:

The ornamental design for a fishing reel, substantially as shown and described.

JOHN V. SCHAFER.
